US00D542141S

(12) United States Design Patent (10) Patent No.: US D542,141 S
(45) Date of Patent:  May 8, 2007

(54) COMBINED BOTTLE AND CAP

(75) Inventors: Matthew Scott Okin, Cresskil, NJ (US); Mark Dieter Dziersk, Winnetka, IL (US); Raymond Michael Flraig, Stamford, CT (US)

(73) Assignee: Conopco, Inc., Englewood Cliffs, NJ (US)

() Term: 14 Years

(21) Appl. No.: 29/234,987

(22) Filed: Jul. 26, 2005

(51) LOC (8) Cl. 09-01

(52) U.S. Cl. D9/529; D9/435; D9/452

(58) Field of Classification Search D9/552, D9/516, 529, 574, 550, 435, 558, 562, 565, D9/549, 446, 452, 575; 215/220, 660, 675, 215/669

See application file for complete search history.
